UNITED STATES PATENT OFFICE.

MARK LEV, JR., OF LOS ANGELES, CALIFORNIA.

TROLLEY.

1,140,689.

Specification of Letters Patent.

Patented May 25, 1915.

Application filed July 22, 1914. Serial No. 852,528.

To all whom it may concern:

Be it known that I, MARK LEV, Jr., a citizen of the United States, residing at Los Angeles, in the county of Los Angeles, State 5 of California, have invented new and useful Improvements in Trolleys, of which the following is a specification.

This invention relates particularly to a novel form of support and electrical contact for a trolley wheel or the like; and the object of my invention includes the provision of a trolley in which means are provided for giving the trolley wheel a long life, for making good electrical contact with 10 the wheel, and for immediate and easy accessibility to the various parts for cleaning, replacements, etc.

I explain the details of my invention in the following specification, reference being 20 had to the accompanying drawings, in which I show preferred forms of my invention, and in which,

Figure 1 is a section showing one form of my improved trolley, Fig. 2 is a section 25 taken as indicated by line 2—2 of Fig. 1, Fig. 3 is a partial section taken as indicated by line 3—3 of Fig. 2, Fig. 4 is a section taken as indicated by line 4—4 of Fig. 1, Fig. 5 is a section similar to Fig. 1 showing 30 another form of my improved trolley.

In my preferred form shown in Figs. 1 to 4, I have shown a trolley harp at 10, which harp may be of the ordinary and usual configuration except as hereinbefore noted. In 35 this form of my device the harp 10 has two arms 11 and 12; and in the arm 12 I mount my contact and shaft carrying head 13 while in the arm 11 I mount a stationary contact plate 14, as is best shown in Fig. 1. The 40 hollow shaft 15 upon which the wheel 16 revolves is permanently and rigidly mounted in the head 13 as shown in Figs. 1 and 3; and this hollow shaft may be the reservoir for any suitable lubricant which finds exit 45 to the outer surface of the shaft 15 through the lubricating openings 16a. The shaft 15 is rigidly mounted at one end in the head 13 and in the other end it projects into the opening 17 in the opposite arm 11 of the 50 harp, the shaft being thus rigidly supported when the head is in its normal position as shown in Fig. 1. The wheel 16 is provided with two contact surfaces at the ends of its hub, preferably formed by disks 18, one on

each end of the hub, these disks being 55 secured to or incorporated with the wheel in any preferred manner. One of these contact disks presses against the stationary contact plate 14, while the other is engaged by a contact plate 19 which is mounted on the 60 head 13 in a manner to be hereinafter described.

The head 13 is circular in general configuration and fits into a corresponding circular opening 25 in the harp arm 12. The head 65 has two extensions or lugs 26 with inwardly extending lugs 27 on their outer ends, which lugs 27 are normally adapted to rest in recesses 28 in the arm 12. These recesses 28 are located at the ends of circular slot 29; 70 and at the other end of these circular slots there are enlargements 30 in the form of apertures through which the lugs 27 may be passed when the head is put in or taken out of normal position. In order to remove the 75 head from the position shown, it is necessary to press the head inwardly by an amount measured by the depth of the recesses 28, to then rotate the head so as to bring the lugs 27 opposite the apertures 30 80 and to then pull the head outwardly passing the lugs 27 through the apertures 30. It will particularly be noted that the head cannot be removed from the arm without the initial inward movement of the head to 85 toward the trolley wheel in a line parallel to the length of the shaft 15. Suitable spaces and allowances are made at all points for the inward movement of the head and of the shaft 15 for removal in the manner specified. 90

The contact disk 18 shown at the left in Figs. 1 and 3 is engaged, as hereinbefore noted, by the contact plate 19. This contact plate 19 is loosely mounted on a mounting plate 35 secured to the inner face of the 95 head 13 in the manner shown, by screws 36, or any other suitable means. The contact plate 19 has extensions 37 and lugs 38 adapted to pass through apertures 39 in the mounting plate 35; and after the lugs are 100 passed through these apertures, a rotative movement of the contact plate relative to the mounting plate will pass the extensions 37 into a restricted portion 39a of the apertures 39, so that the contact plate cannot 105 be removed until it is turned back to its original position. I have shown in Fig. 4 that the lugs 38 are slightly larger than the

extensions 37. The extensions 37 are of such size, in a direction circumferentially about shaft 15, that they pass easily through apertures 39, while the lugs 38 are larger in circumferential measure than the apertures 39 in the corresponding dimension; so that it is necessary to tip the contact plate 19 and the lugs 38 somewhat in order to pass them through the apertures. It is obvious, from 10 the position of the contact plate when the device is assembled, that the contact plate cannot be so tipped until the head 13 is removed from the device. In other words, although I provide for easy removal of the 15 contact plate when it is desired to take the device apart, it is impossible that it should be accidentally removed while the device is assembled and in operation. It will be noted that the revolution of the trolley wheel tends 20 to rotate the contact plate in the direction shown by the arrows in Figs. 2 and 4, tending to carry the extensions 37 to the positions shown in Fig. 4 and tending to carry the extensions 26 to the positions shown in 25 Fig. 2. Thus, the rotational tendency is utilized to hold the parts in such positions that it is impossible for any of them to disconnect from the other parts.

It will be noted in Fig. 1 that the contact 30 plate 19 has a certain amount of movement parallel to the shaft 15; that is, the contact plate is loosely mounted on the mounting plate 35 so as to allow a slight relative movement. A spring recess 40 is formed in the 35 head 13 and a spring 41 therein is confined between the outer wall 13^a of the head and a washer 42, which washer presses against the lugs 38 of the contact plate 19, thus pressing the contact plate into direct and efficient contact with the contact disk 18 on the end of 40 the wheel hub. At the same time this spring 41 presses outwardly on the head so as to hold its lugs 27 in the recesses 28. This single spring performs two functions, pressing 45 the head outwardly to hold it in proper position and pressing the contact plate inwardly to hold it into proper engagement with the contact disk 18 of the wheel. The wheel itself is pressed to the right in Fig. 1 50 by the action of the spring so that its other contact disk 18 is pressed into proper engagement with the stationary permanent contact plate 14 on the arm 11 of the harp.

From the foregoing the fundamental features of my invention may be clearly understood. The minor structural features thereof may be varied according to conditions. I have shown a typical variation of my invention in Fig. 5, consisting primarily of the 60 provision of two heads 13, each constructed in all essentials like the head 13 shown in Fig. 1 and each carrying one half 15^a of the complete shaft for the trolley wheel 16. Each of the heads is removable as in the 65 form shown in Fig. 5, whereas in Fig. 1 only

one side is provided with a removable head and the whole shaft is removed with that one head.

Among other features, I wish to particularly draw attention to the fact that my improved trolley is constructed with no projections which may catch upon the trolley wire or suspending wire; that my improved trolley is simple in its construction and that it affords means for providing long life for the 75 wheel and providing good electrical contact therewith and for providing easy and immediate access to any and all of the parts.

Having described my invention, I claim:—

1. The combination of a wheel and supporting frame therefor, a stationary removable contact carrying head mounted on the frame and removable therefrom only by movement toward the wheel, a contact plate movably mounted in the head and adapted to press against the wheel, and a spring in the head exerting force outwardly on the head away from the wheel and inwardly on the contact plate toward the wheel.

2. The combination of a wheel and a supporting frame therefor, a stationary removable contact and shaft carrying head mounted in the frame and removable therefrom only by movement toward the wheel, a shaft for the wheel carried by said head, a contact plate mounted in the head with freedom to move with reference to the head to and from said wheel and adapted to press against the wheel, and a spring in the head confined between the head and said contact plate and exerting force outwardly on the head away from the wheel and inwardly on the contact plate toward the wheel.

3. The combination of a wheel and a supporting frame therefor, a stationary removable contact carrying head mounted in the frame, said frame having slots therein with recesses extending outwardly away from the wheel, lugs on said head adapted to pass through said slots and fit into said recesses, the lugs being removable from the recesses only by inward movement of the head toward the wheel, a contact plate mounted in the head with freedom to move with reference to the head to and from the wheel and adapted to press against the wheel, and a spring confined between the head and the contact plate exerting force inwardly on the contact plate to press it against the wheel and outwardly on the head to press it away from the wheel.

4. The combination of a bifurcated frame, a wheel shaft removably mounted at one end in one of the furcations of the frame, a wheel on said shaft between the furcations, a removable shaft and contact carrying head mounted in the other furcation, the other end of the shaft being rigidly mounted in said head, said head being removable from said frame furcation only by movement inwardly

toward the wheel, a stationary contact plate mounted on the one furcation against which the wheel may press, another contact plate mounted in said head and movable with reference thereto to and from the wheel, and a single spring means for pressing outwardly on the head and inwardly on said contact plate.

5. The combination of a bifurcated frame, 10 a wheel shaft removably mounted at one end in one of the furcations of the frame, a wheel on said shaft between the furcations, a removable shaft and contact carrying head mounted in the other furcation, the other end of 15 the shaft being rigidly mounted in said head, said frame furcation having a slot therein with a recess extending outwardly away from the wheel, a lug on the head extending through said slot and resting in 20 said recess, the lug being removable from the recess only by inward movement of the head toward the wheel, a contact plate mounted in the head with freedom of movement with reference thereto to and from 25 the wheel, said plate adapted to be pressed into contact with the wheel, and a spring confined between the head and the contact plate exerting force inwardly on the contact

plate to press it against the wheel and outwardly on the head to press it away from the wheel.

6. The combination of a wheel and a supporting frame therefor, a stationary removable head on the frame, a shaft for said wheel rigidly mounted on and supported by 35 said head, said frame having a slot and a recess extending away from said wheel, a lug on the head adapted to pass through the slot and rest in said recess so that removal of the lug from the recess requires movement of the head parallel to the wheel shaft toward the wheel, and a contact plate mounted in the head with freedom of movement relative thereto to and from the wheel, and a spring confined between the head and 40 the contact plate pressing the contact plate inwardly toward the wheel and pressing the head outwardly away from the wheel.

In witness that I claim the foregoing I have hereunto subscribed my name this 14th 50 day of July 1914.
